PROJECTILE TRAPPING METHOD AND APPARATUS

Irving R. Gilson, Liverpool, N. Y., assignor of one-fifth to Theodore E. Simonton, Syracuse, N. Y.

Application July 28, 1943, Serial No. 496,522

11 Claims. (Cl. 73—51)

This invention relates to projectile trapping, and relates more particularly to the trapping of projectiles projected at high velocity substantially along a preselected trajectory, as in the testing of firearms during manufacture by actual firing.

For such test firing of firearms, it has been customary to employ a sand trap in which the bullets are caught and stopped in a pile of sand. Such sand traps have numerous, well-recognized objections. The bullets accumulate in the sand, forming masses of metal apt to cause a later bullet to ricochet, and hence the bullets must be sifted out of the sand frequently. This is a messy and unpleasant operation and is even dangerous to the health of the workmen, as the successive impacts of the bullets pulverize the sand to the fineness of flour. When too much of the sand has thus been pulverized, the sand must be replaced. As the sand must be clean, fine and dry in order to work effectively, the replacement of the sand constitutes a heavy operating cost, a special drying oven often being required to dry the sand as shipped in before it can be used. The sand trap must be put in some remote location, such as an open field or a factory roof-top, as the flour produced floats in the air and is very abrasive, as well as dangerous to health. The used sand is simply a waste product, and must be carted away to a dump. The bullets recovered from the sand are so impregnated with particles of sand that the metal has little, if any, value as scrap metal. Moreover, the original installation of a sand trap is fairly expensive, due principally to the construction features required for safety and to keep the sand dry in an out-of-doors location.

According to my invention, all of the above difficulties are overcome. The bullets are projected into a comparatively slowly flowing, compressible stream of mixed liquid and gas confined in and substantially filling a pipe of moderate diameter and length. The compressible flowing stream absorbs the impact of the bullets and reduces their velocity to substantially that of the flowing stream, whereupon the stream and the bullets are discharged into a reservoir from which the liquid may be pumped for re-use and from which the collected bullets may be removed periodically in a clean condition in which they command a good price as scrap metal. My trap is safe and eliminates all dangerous ricochetting; is entirely clean and hence offers no threat to health or to nearby machinery; is more convenient to use than a sand trap; costs somewhat less

to install and much less to operate than a sand trap; and has the additional advantage of the recovery of usable scrap metal.

Other objects and advantages of my invention will be apparent from the following description and the accompanying drawings, in which:

Figure 1 is a side elevation, partially in section, of a bullet trap according to my invention;

Figure 2 is a detail section taken on the line 10 2—2 of Figure 1;

Figure 3 is a section taken on the line 3—3 of Figure 2;

Figure 4 is a detail plan view taken on the line 15 4—4 of Figure 1; and

Figure 5 is a detail section taken on the line 5—5 of Figure 1.

Referring more particularly to the drawings, my bullet trap comprises a target tube 10 conveniently formed of three pipe sections secured together by customary flanges and bolts, constituting respectively the nozzle section 11, the shock section 12 and the tail section 13. These sections may be made of appropriate lengths of standard 4" pipe, the nozzle section 11 being conveniently made of a 33" length flanged at only one end, the shock section 12 of a 37" length of extra heavy wall thickness flanged at both ends, and the tail section 13 of a 10' length flanged at only one end.

30 The nozzle section 11 is provided with a plurality of nozzles 14, conveniently four in number, the construction and arrangement of which are shown in detail in Figures 2 and 3. As there illustrated, each nozzle 14 comprises an outer

35 casing 15 consisting of a piece of 2" pipe welded into a suitable aperture 15' in the wall of the nozzle section 11 so that the axis of the casing 15 forms an acute angle of preferably seventeen to twenty degrees with the axis of the nozzle section 11. Within the casing 15 is located a

40 1 1/4" nozzle tube 16 provided near its inner end with a guide ring 17 secured thereto and at its outer end with a 1 1/4" pipe coupling 18 threaded thereon. The inner end 19 of the tube 16 is

45 preferably cut off square, reamed smooth and slightly flattened as shown, so as to deliver a smooth, solid stream of water. Before assembly, both the guide ring 17 and the coupling 18 are machined to form a press fit inside the casing 15.

50 The tube 16, the guide ring 17 and the coupling 18 may then be pressed into the casing 15 as a unit. The inner end 19 is preferably so located as barely to project at one side into the opening 15', as illustrated in Figure 3.

55 The four nozzles 14 are preferably equally

spaced around the circumference of the nozzle section 11 to form two diametrically opposed pairs of nozzles, and the nozzles of one pair are preferably located two inches in advance of the nozzles of the other pair, as best shown in Figure 3.

To the couplings 18 are connected, by suitable connections such as 1½" unions 20, lengths of flexible 1½" hose 21, the other ends of which are joined by 1½" unions 22 to a 3" manifold 23, best shown in Figure 4. The 3" pipe 24 supplies water for the nozzles to the manifold 23. The pipe 24 is connected with the outlet of a pump 25 driven by a prime mover such as an electric motor 26, and is preferably provided with a pressure regulating valve 27 and a pressure gauge 28. The pump 25 may have a capacity of 150 gallons per minute at a 30 foot head.

The outlet end of the tail section 13 is threaded into a 4" coupling 30 welded in an end wall of a steel tank 31. The tank 31 may conveniently be 8' long, 4' wide and 3'6" high. The tank 31 is strongly made of heavy steel and, as a precaution against accidents, is provided with an inverted trough 32 made of 1½" armor plate, located over the inner end of the coupling 30 and inclined downward into the tank. The inner end of the trough 32 may be supported by a hook 33 hung on a rod 34 extending across the top of the tank. As a further safety measure, a baffle plate 35, likewise of 1½" armor plate, is located at the rear of the tank 31, the baffle plate 35 being substantially coextensive with the rear wall of the tank 31 and preferably inclined as illustrated. The tank 31 is also provided with a drain 36 controlled by a suitable shut-off valve. A pipe 37 is connected to the tank 31 near its bottom and to the inlet of the pump 25. The tank 31 is also provided with an overflow pipe 38 leading to a suitable sewer.

The nozzle section 11 is provided at its bottom near its inlet end with a drain aperture 40, to which is connected a return pipe 41 discharging into the tank 31.

The outlet end of the tube 10 is supported by the coupling 30 and the tank 31 as described above, and further support for the tube 10 may be provided by the post 45. As shown in Figure 1, the post 45 may also support the overflow pipe 38 and the return pipe 41. A standard 46, conveniently made of pipe fittings, may be used to support the manifold 23 and its associated parts.

The bullet trap above described is preferably located in a separate room to which access may be obtained only through a suitably locked door, and several such traps may conveniently be installed side by side in the same room. Warning signals are preferably provided telling the testing operators not to fire while the door of the trap room is unlocked.

The wall of the trap room opposite the inlet end of the trap is indicated in Figure 1 at 50. An aperture 51 is provided in this wall through which may be inserted the barrel 52 of the machine gun 53 or other firearm to be tested, suitable clearance for recoil of the gun being provided by the aperture 51 as indicated in Figure 1. The machine gun 53 is securely fastened for test firing to a fixed stand 54 diagrammatically illustrated in Figure 1, the stand 54 being so located that when the firearm to be tested is secured thereto, its muzzle will project through the aperture 51 in alignment with the axis of the tube 10, so that the trajectory of the bullet, which is nearly flat

near its origin, will substantially coincide with the axis of the tube 10.

As illustrated in Figure 1, the muzzle of the barrel 52 is preferably spaced a few feet from the inlet end of the tube 10. During operation of the trap, this space is preferably deluged with water from water sprays, not illustrated, for the purpose of laying any unburned powder issuing from the gun muzzle. This water, carrying the powder, is permitted to run off to waste through sewer connections, not illustrated, in the floor of the trap room.

In operation, the tank is filled with water to approximately the level of the overflow pipe 38, 15 and to this water there is preferably added a so-called soluble oil, such as is used as a cutting oil for lubricating metal parts to be machined, in the proportions of one gallon of soluble oil to 400 gallons of water. The pump 25 is then started, 20 and the pressure valve so regulated that the pressure gauge 28 shows a pressure of, for the pipe sizes above described, in the neighborhood of 4½ pounds per square inch gauge pressure. This pressure is less than that necessary to produce 25 solid liquid flow in the tube 10, and it will be observed from the dimensions given above that the cross-sectional area of the four nozzle tubes 16 is less than that of the tube 10. As a result 30 of these conditions and of the angular arrangement of the nozzles 14, air is aspirated through the inlet end of the nozzle section 11 and a stream of commingled water and air flows through the tube 10 toward the coupling 30, discharging into the tank 31. This stream substantially fills the 35 shock section 12 and the tail section 13 of the target tube 10, but very little water flows back toward the inlet end of the nozzle section 11, and what little does is drained into the tank 31 through the return pipe 41.

40 The stream of mixed water and air thus created in the tube 10 flows in the same general direction as the bullet trajectory and is compressible, and is thus enabled to take the impact of a series of bullets fired in rapid succession 45 from the machine gun 53 or the like. A bullet trap as described above has been successfully used with both .30 caliber and .50 caliber machine gun bullets. The .50 caliber bullets have an impact force in the neighborhood of five tons. 50 The compressible flowing stream of air and water cushions this impact and absorbs its force by compression of the air bubbles. It is possible that a rise in pressure in the tube 10 caused by the impact of the bullet creates a condition similar 55 to that in the eduction pipe of an air-lift pump, in which the water and the air, as is well known, form alternate layers or pistons. This, however, is purely speculative, and has not been checked.

The shock caused by the impact of the bullets 60 largely occurs in the few feet of the tube 10 immediately beyond the nozzle assembly. It is for this reason that this section 12 of the tube 10 is called the shock section and is made of extra heavy pipe. There is a tendency for the 65 bullets to be deflected by the stream of water and air and to strike against the wall of the shock section. This result is evidenced by the deformed shape of the bullets recovered from the tank 31 and also by marks on the inside of the shock section. Such marks do not appear in the tail section, indicating that the bullets lose most of their kinetic energy during their passage through the shock section. With .30 caliber ball ammunition, the marks are very slight, and a shock 70 section of ordinary extra heavy cast iron 4" pipe 75

is amply strong to stand the strain and will last indefinitely. With .50 caliber ball ammunition, the marks are definitely heavier, and the striking of the bullets against the inside of the shock section is apt to cause such a pipe to split after perhaps a number of weeks of daily service. The split is usually a single thin crack several inches long, and does not prevent the functioning of the trap, doing no harm aside from a leakage of water. It is desirable, however, to shut down the trap before the split becomes larger, and insert a new shock section. Due to the construction of the trap, this is a simple operation requiring only a few minutes.

With .50 caliber armor piercing ammunition, the marks above referred to became long gouges in the inside of the shock section, and greatly decrease its life. The use of the trap is therefore not recommended with such ammunition, although it is possible to operate with it, and such bullets have been satisfactorily trapped as above described. It seems probable that the gouging problem could be overcome by using a chilled steel shock section. Fortunately, however, it is not ordinarily necessary to test machine guns in the factory with armor piercing ammunition.

In the first trap constructed in accordance with my invention, four nozzles were used equally spaced circumferentially around the nozzle section 11 and at the same distance from the end of the nozzle section, and the ends 19 of the nozzle tubes 16 were round. The result was to create a turbulent mixture of air and water at the point where the resultant nozzle streams converged, which is likewise substantially the point at which the bullets were intercepted by the flowing stream. Due to this turbulent condition at the interception point, considerable deflection of the bullets was experienced, and the bullets collected in the tank 31 were quite severely deformed, principally by having their forward ends bent over. By the nozzle assembly described in detail above, in which the nozzle tubes are flattened and arranged in pairs spaced apart longitudinally of the nozzle section, two converging V-shaped streams of water are obtained, one immediately beyond the other, forming in effect two adjacent V's arranged at right angles to one another. As a result of this nozzle construction, the bullet tends to be centered by the converging streams of water at the interception point, and hence there is less tendency for the bullets to be deflected toward the wall of the shock section. This has been demonstrated in practice by the diminution of the marks on the inside of the shock tube and the lessened deformation of the bullets after the foregoing change in the nozzle assembly was made.

My trap has not as yet been used with projectiles larger than .50 caliber. There seems to be no reason, however, why it could not be used to test larger sizes of firearms, but in the case of a decided increase in the diameter of the projectile, it would be desirable to use a larger size pipe for the target tube 10 and to increase the nozzle sizes and the water pressure accordingly. This is for the reason that there is bound to be some deflection of the projectiles, and sufficient space should be provided between the interception point and the wall of the shock tube so that a projectile will be substantially decelerated before it strikes the wall of the shock tube.

The manner in which the bullets are deposited in the tank 31 strongly suggests that they issue

from the tail section 13 at approximately the velocity of the flowing stream. It will be readily apparent that the velocity of the flowing stream is only an exceedingly small fraction of the muzzle velocity of a .50 caliber machine gun bullet, for example, and that, therefore, the bullets have lost all or nearly all of their kinetic energy in the flowing stream before they are deposited in the tank 31.

- 10 In order to clean the bullets out of the tank 31, it is only necessary to drain the tank through the drain 36 and shovel the bullets out of the tank. Even where the trap is in use substantially continuously for the entire working day, it will suffice to do this only at the close of the day. As many as 20,000 rounds of ammunition may be fired before it is necessary to clean out the tank, whereas with the ordinary sand trap, cleaning is usually necessary at the end of each 5,000 rounds.
- 15 Although I have described my invention, in accordance with the patent statutes, specifically and in detail and in the best form now known to me, it will be appreciated that many changes and modifications may be made by those skilled in the art without departing from the spirit of my invention. I desire, therefore, to be limited only by the prior art and the scope of the appended claims.

I claim:

- 20 1. The method of decelerating a projectile traveling at high velocity substantially along a preselected trajectory, which comprises intercepting the projectile at a selected interception point near the origin of said trajectory in a compressible commingled stream of liquid and gas flowing in the general direction of said trajectory at a very slow speed compared to the initial velocity of said projectile, and confining said compressible flowing stream and the projectile laterally in all directions against departure from a limited zone surrounding said trajectory from said interception point to a point where the initial velocity of the projectile has been reduced to a desired extent by said flowing stream.
- 25 2. The method of decelerating a projectile traveling at high velocity substantially along a preselected trajectory, which comprises continuously bringing liquid angularly into said trajectory in the general direction of said trajectory at a selected projectile interception point near the origin of said trajectory, commingling said liquid with gas at said interception point to form a compressible mixture, confining the compressible mixture in a stream, causing said stream to flow in said general direction at a very slow speed compared to the initial velocity of the projectile, said confining being such that the compressible flowing stream and the projectile are confined laterally in all directions against departure from a limited zone surrounding said trajectory, continuing said confining from said interception point to a point where the initial velocity of the projectile has been reduced substantially to the velocity of said flowing stream, and thereafter discharging said stream and the projectile from the confined zone.

- 30 3. In the art of testing fire arms by actual firing resulting in the projection of a bullet at high velocity substantially along a preselected trajectory, the method of trapping such a projected bullet which comprises causing said trajectory to coincide for a small portion of its normal length near its origin with a laterally confined stream of mixed liquid and gas flowing in the general direction of said trajectory at a

very slow speed compared to the muzzle velocity of the bullet, whereby at least the major part of the kinetic energy of the bullet is absorbed in said flowing stream.

4. In the art of testing fire arms by actual firing resulting in the rapid successive projection of bullets at high velocity substantially along a preselected trajectory, the method of trapping such projected bullets which comprises causing said trajectory to coincide for a small portion of its normal length near its origin with a laterally confined stream of mixed liquid and gas flowing in the general direction of said trajectory at a very slow speed compared to the muzzle velocity of the bullets, whereby at least the major part of the kinetic energy of the bullets is absorbed in said flowing stream, and discharging said flowing stream and bullets when moving at substantially the speed of said stream into a reservoir.

5. The method of decelerating a projectile which comprises providing a substantially straight length of pipe having an inlet end open to the atmosphere and an outlet end, producing and introducing near the inlet end of the pipe a stream of mixed liquid and gas substantially filling said pipe and flowing continuously toward and out of the outlet end of the pipe, projecting a projectile to be trapped through the atmosphere into the inlet end of said pipe in the general direction of the length of said pipe at an initial velocity greatly exceeding that of said flowing stream, and absorbing at least the major part of the kinetic energy of said projectile in said flowing stream of liquid and gas, whereby the projectile emerges from the outlet end of said pipe at a velocity not greatly different from that of said stream.

6. The method of decelerating a projectile which comprises providing a substantially straight length of pipe having an inlet end open to the atmosphere and an outlet end, introducing liquid into said pipe adjacent said inlet end in such manner as to aspirate gas from the atmosphere and to produce a stream of mixed liquid and gas substantially filling said pipe and flowing continuously toward and out of the outlet end of the pipe, projecting a projectile to be trapped through the atmosphere into the inlet end of said pipe in the general direction of the length of said pipe at an initial velocity greatly exceeding that of said flowing stream, and absorbing at least the major part of the kinetic energy of said projectile in said flowing stream of liquid and gas, whereby the projectile emerges from the outlet end of said pipe at a velocity not greatly different from that of said stream.

7. A projectile trap for receiving and decelerating a projectile traveling at high velocity substantially along a preselected trajectory, comprising in combination, a length of pipe having an inlet end open to the atmosphere and an outlet end and having an internal diameter considerably greater than the diameter of said projectile and arranged so that its axis substantially coincides with said preselected trajectory, and means for producing a stream of mixed liquid and gas substantially filling said pipe and flowing continuously toward and out of said outlet end of the pipe at a speed greatly less than the initial velocity of the projectile to be trapped, whereby a projectile projected at high velocity through the atmosphere into said inlet end of the pipe along said trajectory will have at least

the major part of its kinetic energy absorbed in said flowing stream.

8. A projectile trap for receiving and deceler-

5 ating a projectile traveling at high velocity sub-
stantially along a preselected trajectory, comprising in combination, a length of pipe having
an inlet end open to the atmosphere and an outlet end and having an internal diameter con-
siderably greater than the diameter of said proj-
10 ectile and arranged so that its axis substantially
coincides with said preselected trajectory, and
means for introducing liquid into said pipe adjacent
said inlet end so constructed and arranged
as to aspirate gas from the atmosphere and to
15 produce a stream of mixed liquid and gas sub-
stantially filling said pipe and flowing continu-
ously toward and out of said outlet end of the
pipe at a speed greatly less than the initial velocity
of the projectile to be trapped, whereby a
20 projectile projected at high velocity through the
atmosphere into said inlet end of the pipe along
said trajectory will have at least the major part
of its kinetic energy absorbed in said flowing
stream.

25 9. A projectile trap for receiving and decelerating a projectile traveling at high velocity substantially along a preselected trajectory, comprising in combination, a length of pipe having an inlet end open to the atmosphere and an outlet end and having an internal diameter considerably greater than the diameter of said projectile and arranged so that its axis substantially coincides with said preselected trajectory, means for introducing liquid into said pipe ad-

30

means for introducing liquid into said pipe adjacent said inlet end so constructed and arranged as to aspirate gas from the atmosphere and to produce a stream of mixed liquid and gas substantially filling said pipe and flowing continu-

ously toward and out of said outlet end of the pipe at a speed greatly less than the initial velocity of the projectile to be trapped, said means comprising nozzles leading into said pipe adjacent said inlet end at circumferentially spaced points and at acute angles to the axis of said pipe, the resulting jet being deflected

45 of said pipe, the combined cross-sectional area of said nozzles being less than the cross-sectional area of said pipe, and means for supplying liquid to said nozzles at a pressure less than that re-

50 to said nozzles at a pressure less than that required for solid liquid flow in said pipe, whereby a projectile projected at high velocity through the atmosphere into said inlet end of the pipe along said trajectory will have at least the major part of its kinetic energy absorbed in said flowing stream.

55 10. A projectile trap for receiving and decelerating a projectile traveling at high velocity substantially along a preselected trajectory,

comprising in combination, a length of pipe having an inlet end open to the atmosphere and an outlet end and having an internal diameter considerably greater than the diameter of said projectile and arranged so that its axis substantially coincides with said preselected trajectory, means for introducing liquid into said pipe, and

65 for introducing liquid into said pipe adjacent said inlet end so constructed and arranged as to aspirate gas from the atmosphere and to produce a stream of mixed liquid and gas substantially filling said pipe and flowing continuously toward and out of said outlet end of the pipe at

70 a speed greatly less than the initial velocity of the projectile to be trapped, said means comprising a pair of opposed nozzles leading into said pipe adjacent said inlet end and at acute angles to the axis of said pipe, a second pair of
75 opposed nozzles leading into said pipe at points

spaced both longitudinally and circumferentially from said first pair of nozzles and at acute angles to the axis of said pipe, the combined cross-sectional area of said nozzles being less than the cross-sectional area of said pipe, and means for supplying liquid to said nozzles at a pressure less than that required for solid liquid flow in said pipe, whereby a projectile projected at high velocity through the atmosphere into said inlet end of the pipe along said trajectory will have at least the major part of its kinetic energy absorbed in said flowing stream.

11. A projectile trap for receiving and decelerating a projectile traveling at high velocity substantially along a preselected trajectory, comprising in combination, a length of pipe having an inlet end open to the atmosphere and an outlet end and having an internal diameter considerably greater than the diameter of said projectile and arranged so that its axis substantially coincides with said preselected trajectory, means for introducing liquid into said pipe adjacent said inlet end so constructed and arranged as to aspirate gas from the atmosphere and to pro-

duce a stream of mixed liquid and gas substantially filling said pipe and flowing continuously toward and out of said outlet end of the pipe at a speed greatly less than the initial velocity of 5 the projectile to be trapped, said means comprising nozzles leading into said pipe adjacent said inlet end at circumferentially spaced points and at acute angles to the axis of said pipe, the combined cross-sectional area of said nozzles 10 being less than the cross-sectional area of said pipe, and means for supplying liquid to said nozzles at a pressure less than that required for solid liquid flow in said pipe, and a reservoir into which said outlet end of said pipe discharges, 15 said reservoir constituting a source of liquid for said liquid supplying means, whereby said liquid may be re-used and whereby a projectile projected at high velocity through the atmosphere into said inlet end of the pipe along said trajectory will have its velocity reduced substantially to the velocity of said flowing stream and 20 will be discharged into said reservoir.

IRVING R. GILSON.
